METHOD OF AND APPARATUS FOR
PILING FABRIC

Frank P. Mackenzie, Bayonne, N. J.; Florence M. Webb, administratrix of said Frank P. Mackenzie, deceased, assignor to Florence M. Webb, Bayonne, N. J.

Application December 12, 1933, Serial No. 702,058

10 Claims. (Cl. 271—73)

This invention relates to a method of and apparatus for piling and laying fabric and the like, and with respect to its more specific features relates to an improved method of and apparatus for superimposing layers of cloth one on top of the other.

It is an object of this invention to provide an apparatus which will enable the operator to superimpose several layers of fabric one on top of the other without distorting or stretching the fabric in any way.

A further object is the provision of a stationary cloth-piling and laying apparatus which will enable tailors and cutters to superimpose several layers of fabric and cut out a pattern from all of the layers at the same time without the usual difference in size and shape resulting from the distortion and stretching of some of the layers of fabric.

Another object is the provision of an improved method of piling cloth which will be simple and economical to carry out and which will eliminate the difficulties, such as the stretching and distortion of the fabric, heretofore encountered in piling cloth.

Among other objects is the provision of an improved cloth-piling apparatus, which will be of inexpensive construction, which will be economically operated over long periods of time with freedom from repair, and which will enable even the unskilled to superimpose layers of fabric without distortion.

Heretofore it has been the practice to pile cloth by first placing a layer of fabric upon a flat surface, laying another layer of cloth directly upon the first layer, and then aligning the two layers.

Because of the frictional resistance between the two layers, the uppermost layer would be slightly stretched in superimposing it upon the first; also, in aligning the two layers of fabric, the frictional resistance between the two layers would cause portions of the fabric to become distorted. These difficulties were greatly multiplied as the number of superimposed layers was increased.

When a pattern was laid out on the uppermost layer of fabric and simultaneously cut out of all the layers, great variations in size and shape necessarily resulted. The present invention, among other objects, contemplates the elimination of these difficulties by interposing a layer of substantially frictionless material between the two layers of fabric while they are being superimposed and aligned. This may be accomplished by first placing a layer of fabric upon a flat surface, advancing a layer of frictionless material

until it is superimposed upon the first layer, then laying a second layer of fabric upon the frictionless material, aligning it with the first layer and permitting it to assume its normal shape and length, and then withdrawing the layer of frictionless material.

For a full understanding of the present invention, reference should be had to the accompanying drawings, in which

Figure 1 is a sectional elevation taken on the line 1—1 of Fig. 2, and showing an apparatus embodying features of the present invention;

Fig. 2 is a plan view of the cloth-piling apparatus showing the substantially frictionless material in advanced position so as to cover the cloth-receiving surface of the apparatus;

Fig. 3 is a plan view showing the substantially frictionless material in retracted position so as to expose the cloth-receiving surface of the apparatus;

Fig. 4 is a detail plan view showing mechanism that may be used in shifting the substantially frictionless material;

Fig. 5 is a detail view in elevation showing the mechanism for shifting the substantially frictionless material;

Fig. 6 is an elevation showing in detail the mechanism for automatically adjusting the height of the fabric-receiving surface;

Fig. 7 is a detail view of the switch mechanism which actuates the apparatus for adjusting the height of the cloth-receiving surface, and

Fig. 8 is a detail view showing a slightly modified form of mechanism for shifting the substantially frictionless material.

Referring now more particularly to the drawings, the numeral 10 indicates generally a table upon which the present apparatus may be mounted. A board 11 is preferably placed upon the table to form a cloth-receiving surface upon which the layers of fabric, indicated by the numeral 12, may be piled. It is to be understood, of course, that the fabric may be piled directly upon the table itself. An aligning edge or straight edge is preferably formed on the table in order to aid in aligning the layers of fabric. The aligning edge illustrated in the accompanying drawings consists of the end 14 of a supporting member in the form of a board 15 suitably fastened to the side of the table. Disposed adjacent the table, and mounted so that it may be shifted back and forth across the top surface thereof, is a member having a broad, smooth, substantially frictionless upper surface, such as a sheet of oilcloth, indicated in the drawings by the numeral 27. The

oil cloth is supported on and carried by a plurality of reciprocating arms, such as the three lazy-tongs 16, supported adjacent the side of the table opposite aligning edge 14. Each pair of lazy-tongs is pivotally connected to two operating handles 17 and 18 by means of pins 19 and 20. It will be seen that by alternately pivoting the handle members in opposite directions, the lazy-tongs may be alternately extended and contracted longitudinally. The outer or free ends of each of the lazy-tongs are pivotally secured to a connecting or supporting strip 21 made out of suitable rigid material, such as steel. The strip 21 extends laterally beyond the lazy-tongs and at each end grooved rollers 22 and 23 are journaled thereto. The grooves in the rollers cooperate or ride upon tracks 24 and 25 formed of metal strips suitably secured to the surface of the table. The rollers 22 and 23 guide the shifting of the lazy-tongs and the supporting strip 21 across the surface of the table as the lazy-tongs are alternately extended and contracted. The rollers also serve as spacers and, therefore, should be of a sufficient circumference to hold the lazy-tongs, 25 the strip 21 and the oilcloth not only clear of the surface of the table, but also clear of the layers of fabric that are piled upon the board 11. One end of the oilcloth 27 is secured to the cross arm 24, by suitable fasteners, such as rivets 26. The oilcloth is extended horizontally over the lazy-tongs and is thence fed over the guide roller 45 suitably journaled, at either end, in plates 93 secured to the ends of the table. At its opposite end, the oilcloth is secured so as to always be held taut regardless of the position of lazy-tongs 16. This may be accomplished either by means of another set of lazy tongs 98, or by means of a spring roller 46. The lazy-tongs 98 are similar to lazy-tongs 16. At their lower ends they are connected by means of a cross strip to which the end of the oilcloth is secured. Each pair of lazy-tongs 98 is controlled by means of a pair of operating handles 55 and 56. The operation of lazy-tongs 98 is synchronized with the operation of tongs 16, so that when lazy-tongs 16 are extended, tongs 98 are contracted, and when lazy-tongs 16 are contracted, lazy tongs 98 are extended. The spring roller 46 disclosed in Fig. 3 may be employed instead of the lazy tongs 98. A spiral spring disposed in the roller tends to normally rotate the roller in a clockwise direction. The oilcloth is wound around the roller and its end is suitably secured thereto by means of rivets or other fasteners. When the tongs 16 are extended 55 so as to shift the oilcloth across the surface of the table, the oilcloth unwinds from the roller against the tension of the spring. When the tongs 16 are contracted shifting the oilcloth back across the table so as to expose its upper surface, the slack of the oilcloth is immediately taken up by the roller 46. The spring of the roller must be sufficiently strong to hold the oilcloth quite taut. This is particularly important when the arms have been extended so as to shift the oilcloth over 60 the table. It will be seen that in this position the spring will be under its greatest tension due to the fact that it has been wound up by the unrolling of the oilcloth. The oilcloth will accordingly be held most rigid when it is fully extended.

The mechanism for operating the lazy-tongs is as follows: A wheel 28 is keyed to the end of a shaft 29. This shaft has keyed to it three worms, designated by the numeral 30. Each of 65 these worms cooperates with a worm gear 31 keyed to a shaft 32. Each shaft 32 is suitably journaled in a metal supporting block 33, which is mounted upon the table 10. Keyed to the other end of the shaft 32, is a bevel gear 34. Bevel gear 34 operates a bevel pinion 35, which is likewise journaled in the member 33, and the bevel pinion 35, in turn, operates another bevel gear 36, also journaled in the block 33. It will thus be seen that rotation of the wheel 28 will cause rotation of the shaft 29 which, in turn, 10 will rotate the worms 30, worm gears 31, shaft 32, and bevel gear 34. The bevel gear 36, which faces the bevel gear 34, will be caused to rotate in the opposite direction to the gear 34, by means of the pinion 35. An axially extending lug 37 15 is formed upon the face of the bevel gear 34 and the operating handle 17 is pivoted thereto. A similar axially projecting lug 38 is formed upon the bevel gear 36 and the operating handle 18 is similarly pivoted thereto. The handle members 17 and 18 are formed with slots 39 and 40, respectively. Fixed pins 41 and 42 ride in these slots and act as guides and pivots for the reciprocating motion of the handle members. Pin 41 which cooperates with handle 17 projects upwardly and is fixedly secured to the member 33. Pin 42 which cooperates with handle 18 projects downwardly and is likewise fixed to the member 33.

Rotation of the opposed oppositely-rotating 30 gears 34 and 36 in the direction of the arrows in Fig. 4, will cause the lazy-tongs to be retracted when the lugs 37 and 38 reach the point 45 in their paths of rotation, as illustrated in dotted lines in that figure. Continued rotation 35 of the two bevel gears in the direction of the arrows, i. e., 34 in a clockwise direction and 36 in a counterclockwise direction, will then cause the lazy-tongs to be gradually extended or advanced until they reach the position shown in 40 full lines in Fig. 4 when they will be completely extended. When the lazy-tongs are contracted laterally they will be extended longitudinally and, likewise, when they have been extended laterally they will be contracted longitudinally. It will be seen that the position of the lazy-tongs is determined by the sliding and pivoting of the operating handles 17 and 18 around the pins 41 and 42. This pivoting, in turn, is controlled by the position of the lug 38 in respect to the pin 42 and the lug 37 in respect to the pin 41. The 50 gears 34 and 36 are so arranged that the lugs 37 and 38 will be directly opposed to each other at the points indicated by the numerals 43 and 44 in Fig. 4.

When the oilcloth has been shifted so as to extend across the surface of the table and is then retracted, the slack is taken up either by the roller 46 or lazy-tongs 98, according to the construction employed. The operation of the roller 46 has been fully explained. There are 60 preferably the same number of lazy-tongs 98 as there are of tongs 16 and their operation is similar to that of lazy tongs 16.

Worm gears 47, driven by the worms 30, are keyed to shafts 48 suitably journaled in vertical projections 49 formed on the members 33. Keyed to the opposite end of each shaft 48, is a bevel gear 50, which, by means of a bevel pinion 51, causes another bevel gear 52 suitably journaled in the member 49, to rotate in the opposite direction. Gears 50 and 52 are similar to the gears 34 and 36 previously described. They are formed with similar axially-extending lugs 53 and 54, having pivotal connection with operating handles 55 and 56, which control the operation 70

75

of the lazy-tongs 98. The handles or levers 55 and 56 are provided with slots in which fixed pins 100 and 101 ride. The operation of this mechanism is the same as that which operates each of the lazy-tongs 16. The gears 59 and 52 and, accordingly, the lugs 53 and 54 rotate in opposite directions causing the alternate extension and contraction of the lazy tongs 98. However, the lazy-tongs 98 work oppositely to lazy-tongs 16. When the lazy-tongs 16 are extended, lazy-tongs 98 are contracted, and when lazy-tongs 98 are extended, lazy-tongs 16 are contracted. It will be seen that this action will cause the alternate shifting of the oilcloth back and forth across the surface of the table.

The wheel 28 may be connected by means of a belt to suitable driving mechanism, such as an electric motor, or to a foot-operated pedal, or, if desired, it may be manually revolved by the operator. Rotation of the wheel 28 causes rotation of shaft 29, worms 30, worm gears 31, shafts 32, and gears 34 and 36. This causes the lazy-tongs 16 to alternately extend and contract, thereby causing the shifting of the oilcloth back and forth across the surface of the table. The oilcloth is held taut and its slack is taken up either by means of the roller 46 or the lazy-tongs 98 which reciprocate oppositely to lazy-tongs 16. The lazy-tongs 16 and the oilcloth 27 should be of sufficient length to be extendable substantially across the table. The number of lazy-tongs employed and the width of the oilcloth employed may be varied in accordance with the length of the strips of fabric to be piled upon the table.

On the opposite side of the table from the mounting of the lazy-tongs, suitable means for clamping the piled layers of fabric in position are provided. The clamping members preferably consist of weights 57, which normally rest on the surface of the table or on the surface of the cloth-receiving board 11. The clamping weights 57 are fixedly secured to a shaft 58 by means of arms 59. The shaft 57 is mounted for vertical shift-movement. Adjacent each end of the shaft 58, downwardly-projecting arms 60 are formed. These arms ride in guideways or slots formed in the supporting board 15. The weights may be manually raised by lifting the shaft 58. They are normally held in clamping position due to gravitational pull. Automatic means are provided whereby the clamping weights are elevated when the lazy-tongs 16 and the oilcloth 27 have been shifted across the table towards the clamping weights. This mechanism comprises a projection or follower 61, secured to each of the arms 60. The followers are operated by means of cams 62 mounted adjacent either end of a shaft 63. When the dwell portions of cams 62 engage the followers 61, the followers and, consequently, the arms 60, shaft 58 and clamping weights 57 are raised upwardly. Also mounted on the shaft 63, is a bevel gear 64, which is driven by another bevel gear 65 keyed to a shaft 66. At the opposite end of the shaft 66 is mounted a sprocket wheel 67, connected by means of chains 68 to another sprocket wheel 69 secured to the shaft 48. By means of the mechanism just described, rotation of the wheel 28 and, consequently, the shaft 29 causes, by means of worm 30, worm gear 47, sprocket 69, chain 68, and sprocket 67, the rotation of shaft 66. The rotation of the shaft 66 causes, by means of the bevel gears 64 and 65, rotation of the shaft 63 and the cams 62. When the cams 62 contact their followers 61, they cause them to raise upwardly which, in turn, will lift the

arm 60, shaft 58, and clamping weights 57. The gearing and driving mechanism is such that the cams 62 will make a single revolution for every revolution of the bevel gears 64 and 36. The cams are so positioned that when the lazy-tongs 16 are being projected outwardly so as to shift the oilcloth across the surface of the table towards the clamping weights 57, the cams will raise the followers 61. As soon as the lazy-tongs begin to shift the oilcloth away from the clamping weights, the cams will release the followers 61, thereby permitting the clamping weights to drop downwardly.

When several layers of fabric have been piled upon the table, it sometimes becomes inconvenient for the operator to work because the plane of operation has been raised due to the thickness of the pile of fabric. In order to overcome this difficulty, mechanism is herein provided whereby the table may be automatically lowered after a predetermined number of layers of fabric have been piled upon the table. To this end, a gear 70 keyed to the shaft 63, cooperates with a gear 71 keyed to a shaft 72. Fixed to the shaft, at its central portion, is a cam 73. A slide 74, riding in a guideway or track formed in the board 15, is formed with a follower or projection 75, which cooperates with the cam 73. In order to normally urge the slide 74 upwardly against the pull of gravity, a counter-weight 76 is secured on the lever 77. The lever 77 is pivoted at 78 to the board 15, and its opposite end engages the under surface of a projection 79 formed on the slide 74 to exert a lifting pressure on it. Fastened to the upper end of the slide 74, is a contact arm 80, which projects upwardly and presses against the face of a slide or arm 81, which is secured to and projects downwardly from the shaft 58. The arm 81 is formed with a contact point 82, which the contact arm 80 engages when the member 81 and the slide 74 are spaced a sufficient distance apart. The contact arm 80 normally engages the members 81 at a point above the contact 82. The cam 73 makes a single revolution for each revolution of the cams 62. It is preferably positioned so that its dwell portion engages its follower shortly after the dwell portions of the cams 62 engage their followers, as illustrated in Fig. 1. Under this arrangement, when the dwell portions of the cams 62 engage the followers 61, raising the shaft 58 and the arm 81 upwardly, the rest portion of the cam 73 cooperates with the follower 75, thereby permitting the counterweight 76 to urge the slide 74 upwardly. This will permit the slide 74 and the arm 81 to be spaced so close together that the contact arm 80 will be well above the contact 82. When the cams continue to rotate and the cams 62 release their followers 61, the arm 81 drops downwardly to its lowermost position. The dwell portion of the cam 73 then contacts its follower 75 and urges the slide 74 downwardly. The slide 74 and the arm 81 will, therefore, still be in approximately the same position relative to each other and the contact arm 80 will not engage the point 82. If, however, several layers of fabric have been placed under the clamping weights 57, it will be seen that the weights 57, the connecting arm 59 and, consequently, the arm 81, will be held in a slightly higher plane after the followers 61 have been released by the cams 62. When the dwell portion of the cam 73 then engages its follower 75, forcing the slide 74 downwardly, the contact arm 80 will then engage the contact point 82, because the arm 81 and the slide 74 are spaced a greater distance apart due to the layers 75

of fabric interposed beneath the clamping weights 57. By adjusting the position of the contact arm 80, it will be seen that its time of operation can be controlled. If the arm 80 is increased in length, a greater number of layers of fabric can be interposed beneath the clamping weights 57 before the contact is closed. Likewise, if the length of the contact arm is decreased, a fewer number of layers of fabric causes the contact to be closed. The contact point 82 is connected, by means of a wire 83, to one terminal of a suitable source of electric current, such as a battery (not shown). The contact arm 80 is connected, by means of a wire 84, to a timer encased in the box 85, which causes the operation of a motor 86. Another wire 82 leads directly from the other terminal of the battery to the timer. Closing of the contact between the arm 80 and the contact point 82, brings into operation the timing device, which causes the motor 86 to operate for a fixed predetermined period regardless of the length of time during which the contact is closed. The motor 86 is connected, by means of suitable gearing, also enclosed in the box 85, to a shaft 88, which has a pair of worms 89 keyed thereto. The worms cooperate with and cause the operation of worm gears 90, which are keyed to vertical shafts 91. Each shaft 91 is suitably journaled in a supporting bracket 92, and is formed at its upper portion 93 with screw threads. This portion extends into an internally-threaded sleeve 94. Rotation of the shaft 91 from right to left in Fig. 1, will cause the sleeve to rise upwardly. Rotation of the shaft in the opposite direction will cause the sleeve to drop downwardly. Each of the sleeves 94 is secured to plates 95, which are suitably fastened to the under side of the table. It will be seen that the brace 92, shaft 91, and sleeve 94, serve as adjustable supporting legs for the table. In addition to these legs, additional legs or supports 96 are provided to add additional stability to the table. The legs 96 are hollow so as to permit shafts 97 secured to the under face of the table, to telescope into them. By means of this mechanism it will be seen that when contact arm 80 engages contact point 82, the timing mechanism disposed in box 85 is energized, causing the motor 86 to operate for a fixed period. The motor 86 causes shaft 88, worms 89 and shaft 91 to rotate, thereby lowering the table. The amount that the table is automatically lowered may be regulated by adjusting the timing mechanism. In addition to the automatic means for controlling and regulating the height of the table, a suitable hand-operated switch mechanism (not shown) for controlling the motor may be provided, whereby the operator may at any time raise or lower the table as he may desire.

The operation of the apparatus above described is as follows: The board 11 is placed upon the table 10 adjacent the aligning edge 14, and with its one edge under the clamping weights 57. The lazy-tongs 16 and, consequently, the layer of substantially frictionless material 27, are completely retracted by means of the wheel 28 so as to completely expose the surface of the board 11. A layer of fabric is placed upon the board with its one side edge flush with the aligning edge and beneath the clamping weights 57. The fabric is preferably placed so that its side edges are parallel to the aligning edge and so that its ends extend towards the ends of the table. The wheel 23 is then rotated so as to project the lazy-tongs 16 outwardly and thereby shift the layer of oilcloth 27 across the table thereby covering the first layer

of fabric. Due to the rollers 22 and 23 and the tracks 24 and 25, the lazy-tongs and substantially frictionless material will be spaced above the board and above the layer of fabric. As the arms are projected outwardly the clamping weights automatically rise up. When the oilcloth is completely extended by means of the lazy-tongs, another layer of fabric is placed on top of the oilcloth. It is aligned with the first layer of fabric and allowed to assume its normal shape. Because of the slippery or substantially anti-friction surface of the oilcloth, there will be no tension or pull upon the layer of fabric, and it will readily assume its normal shape. The wheel is again turned. This further turning of the wheel 28 will cause the contracting of the lazy-tongs 16, which, in turn, will cause the layer of frictionless material to be shifted back across the table so as to completely expose the cloth-receiving board 11. As soon as the lazy-tongs begin to contract, the clamping weights 57 will drop downwardly and grip both layers of fabric adjacent one edge. As the layer of substantially frictionless material withdraws from beneath the uppermost layer of fabric, it will not distort or stretch the fabric due to the almost total absence of friction. It will, however, aid in straightening the fabric out and causing the fabric to assume its normal shape. When the oil cloth has been shifted to one side so as to completely expose the board 11 and the fabric thereon, it will be found that the second layer of fabric has been deposited on the first layer in perfect alignment and also without being stretched or distorted. This operation may be repeated to successively deposit additional layers of fabric upon the pile until a pile having the desired number of layers has been formed. Thus it will be seen that by the above-described apparatus and method piles of fabric having many layers may be easily and speedily formed without in any way stretching or distorting the fabric.

It is to be understood, of course, that many modifications may be made in the illustrated and described embodiment of the invention, as, for instance, other materials than oilcloth having a slippery or substantially frictionless surface, such as highly glossed paper, may be employed, and other means for shifting the oilcloth may be employed.

What is claimed is:

1. A fabric piling apparatus comprising, in combination, a fabric-receiving surface, an aligning edge formed adjacent one side of said surface, a shiftable member having a substantially frictionless surface mounted on the outer side of said surface, and means for advancing said member across said surface towards said aligning edge and for retracting said member across said surface away from said aligning edge.

2. An apparatus of the character described comprising, in combination, a flat surface, a layer of slippery surfaced material, a plurality of arms for supporting and shifting said layer of material across said flat surface, and guide means for guiding said shifting of the layer of material across the flat surface.

3. An apparatus of the character described comprising, in combination, a table, a plurality of shiftable arms mounted along one edge of said table, a member having a broad, substantially frictionless upper surface secured to and carried by said arms, and means for shifting said arms back and forth across said table.

4. An apparatus of the character described comprising, in combination, a table, lazy tongs

5 mounted adjacent one edge of said table, a sheet of oilcloth secured to the free end of said tongs, and means for extending and contracting said tongs to cause said oilcloth to shift across the surface of said table.

10 5. An apparatus of the character described comprising, in combination, a table, lazy tongs mounted adjacent one edge of said table, a sheet of oilcloth secured to the free end of said tongs, and means for extending and contracting said tongs to cause said oilcloth to shift across the surface of said table, said means comprising a pair of opposed oppositely-rotating members, each having connection with one handle of said

15 6. An apparatus of the character described comprising, in combination, a table, a member having a substantially frictionless upper surface shiftable back and forth across the surface of said table, clamping means formed adjacent one edge of said table, and means cooperable to cause said clamping means to open as said member approaches the clamping means and to cause said clamping means to close as said member shifts away from said clamping means.

20 7. An apparatus to be used in piling layers of fabric one on top of the other comprising, in combination, a table for receiving the layers of fabric, clamping means disposed adjacent one edge of the table for holding the layers of fabric in position, a sheet of oilcloth mounted adjacent the surface of said table, means for shifting said oilcloth across the surface of said table towards and away from said clamping means, means responsive to said last-named means for opening said clamping means as the oilcloth is shifted towards the clamping means, and for closing said clamping means as the oilcloth is shifted away from it, means including a switch operable by said clamp-

25 ing means for lowering said table when the layers of fabric reach a predetermined height, and means to render said last-named means inoperative when said clamping means is open.

8. The method of piling layers of fabric one 5 on top of the other comprising laying a layer of fabric upon a flat surface, placing a layer of slippery surfaced material over the layer of fabric, laying another layer of fabric upon the layer of slippery surfaced material, aligning the 10 second layer of fabric with the first layer of fabric, and withdrawing the layer of slippery surfaced material.

9. The method of piling layers of fabric one 15 on top of the other comprising laying a layer of fabric upon a flat surface, placing a sheet of oilcloth over the layer of fabric, laying another layer of fabric upon the sheet of oilcloth, aligning the second layer of fabric with the first layer of fabric, gripping the layers of fabric adjacent 20 one edge, and withdrawing the sheet of oilcloth.

10. An apparatus to be used in piling layers of fabric one on top of the other comprising, in combination, a fabric receiving surface, clamping means disposed adjacent one edge of the surface, for holding the layers of fabric in position, a shiftable member having a substantially frictionless surface mounted adjacent said fabric receiving surface and shiftable towards and away from said clamping means, means controlled by 25 said last-named member for causing said clamping means to open as said member is shifted towards said clamping means and to close as said member is shifted away from said clamping means, and means operated by said clamping 30 means for lowering said surface when the layers of fabric reach a predetermined height.

FRANK P. MACKENZIE.
